1 Claim. (Cl. 18—34)

One of the greatest drawbacks in the process of compressing materials in powder form into briquettes, is the occurrence of fissures in the compressed mass.

5 The formation of these fissures can only be prevented if the state of tension existing within the briquettes can be at all times controlled, that is, not left undisturbed but made to develop in a predetermined way.

10 It is to be borne in mind, however, that there is a difference between the state of tension which exists during the compressing action, i. e. during the period in which the pressure to be exerted on the mass to be compressed is being raised from 15 atmospheric pressure to maximum pressure, and the state of tension existing during relief of pressure, i. e. during the period extending from the attainment of the maximum pressure to the moment at which the pressure is reduced to atmospheric.

If a substance, such as, coal dust, blast furnace dust or petroleum coke, is compressed from all directions and the pressure components each of which is acting on a unit of the briquette surface 25 are continually kept equal and the pressure is then relieved while also keeping equal the pressure components acting on each unit of the briquette surface, the formation of fissures in the briquette will be prevented.

30 By this method of compressing, the briquette thus formed will become isotropic which means that the elastic properties of the briquette will be at all times equal in all directions.

For carrying out this method of pressing and 35 relieving the pressure very complicated presses are however, required. Such presses are of the type in which the compression chamber is enclosed by a number of compression plates, each of which is separately movable.

40 My invention now has for its purpose to obtain the desired results with a considerably simplified construction of the presses required. As a specific form of mold for practising the method according to the present invention, a matrix, the 45 generatrix of which satisfies the equation,

$$\left(\frac{x}{x_0}\right)^{\lg(1+\epsilon_a)} = \left(\frac{y}{y_0}\right)^{\lg(1+\epsilon_r)}$$

wherein

50 $\epsilon_a=0.10$, $\epsilon_r=0.065$, $x_0=22.5$ millimeters and $y_0=27$ millimeters, is used.

55 In solving this problem I have started from the principle that it is permissible to deviate from the requirement to keep the briquette contin-

uously in a homogeneous state of tension, as it has been ascertained that deviations within certain limits of the homogeneous state of tension may be tolerated.

My invention which will be further described 5 hereinafter is based on the following considerations:

In the equations found herebelow the symbols used are as follows:

$\lg$	=logarithm	10
ϵ	=elongation per unit of length	
ϵ_r	=radial elongation per unit of length	
ϵ_a	=axial elongation per unit of length	
ϵ_t	=tangential elongation per unit of length	15
σ	=tension (indicated at the end of the arrow normal to the long side in Fig. 2)	
σ_r	=radial tension	
σ_a	=axial tension	20
σ_t	=tangential tension	
E	=modulus of elasticity	
m	=coefficient of contraction	25
τ	=shearing stress	
φ	=angle between tangent at point and X axis (see Fig. 1).	30

If a substance is compressed in a cylindrical matrix or press die between two axial rams, it can be ascertained that the resulting briquette is not isotropic (the elastic properties being unequal in all directions). It appears that when 30 relieving the pressure the expansion in the direction of compression (axial direction) exceeds that in a direction perpendicular thereto (radial direction). During the pressing in one direction, a departure from the homogeneous condition of tension occurs in such a manner that, axially, larger pressures are produced than radially. During the compression, however, the departure from the homogeneous condition of tension is of secondary importance. When the compression rams are retracted then the axial pressure decreases in a higher degree than the radial pressure. There is, however, a moment, at which the condition of tension, apart from the friction along the walls, 35 is again homogeneous. If, however, the compression rams are further retracted, then the axial pressure will drop beneath the radial pressure and then a departure from the homogeneous condition of tension occurs again. In order to prevent a breaking up of the briquette said departure should be suitably limited. This can be obtained by using a matrix, in which according to the invention the interior wall of the mold is formed by the bounding surface of a solid of 40 45 50 55

revolution, the generatrix of which surface satisfies the equation:

$$\left(\frac{x}{x_0}\right) \lg (1+\epsilon_a) = \left(\frac{y}{y_0}\right) \lg (1+\epsilon_r)$$

5 with respect to a coordinate system, the y -axis of which coincides with the axis of rotation.

The invention will be further explained with the aid of the drawing in which

10 Fig. 1 represents a perspective view, partly in section of a pressing mold or matrix according to the invention.

Fig. 2 represents a particle of the material belonging to the outer surface of the briquette, the 15 forces acting on the same being indicated by arrows.

Assuming now that a substance is contained in 20 a cylindrical compression-space denoted by a dotted line 1 in Fig. 1 under a bi-axial (X- and Z-axes) homogeneous condition of tension, while on said substance a specific surface pressure p is exerted in axial direction and a specific surface pressure q in radial direction, then in any point of the cylinder the same conditions of tension 25 and deformation will occur, which are characterized by the radial, tangential and axial tensions

$$\sigma_r = q; \sigma_t = q; \sigma_a = p$$

and the corresponding specific strains

30 $\epsilon_r; \epsilon_t = \epsilon_r$ and ϵ_a .

If a pressure is exerted on a cylinder in an axial direction only, it will be obvious that the tensions occurring in a cross section of this cylinder, perpendicular to the axis will all be equal, so that indeed under these circumstances it also may be said that the radial and tangential tensions are equal.

The tension and deformation value in the case 40 of a homogeneous and isotropic substance are correlated as follows:

$$E\epsilon_r = E\epsilon_t = \sigma_r - \frac{1}{m}(\sigma_r + \sigma_a) = q - \frac{1}{m}(p+q)$$

$$45 E\epsilon_a = \sigma_a - \frac{1}{m}(\sigma_r + \sigma_t) = p - \frac{2}{m}q$$

The requirement now is to so determine the meridian curve 2 that in the case of a deformation of the part bounded by said meridian curve 50 under the load p, q each point of the curve 2 again reaches said curve.

The point x_0, y_0 after deformation will lie at

$$x_1 = (1+\epsilon_r)x_0$$

$$55 y_1 = (1+\epsilon_a)y_0$$

The point coinciding in the deformed condition with x_1, y_1 will lie at

$$x_2 = (1+\epsilon_r)^2 x_0$$

$$60 y_2 = (1+\epsilon_a)^2 y_0$$

Continuing in this way a plurality of points can be determined with the general coordinates

$$65 x_n = (1+\epsilon_r)^n x_0$$

$$y_n = (1+\epsilon_a)^n y_0$$

which points must all lie on the curve to be determined. If from the last equations the parameter n is eliminated then it appears that the coordinate of the points $x_0, y_0, x_1, y_1, x_2, y_2, \dots, x_n, y_n$ all satisfy the equation

$$\left(\frac{x}{x_0}\right) \lg (1+\epsilon_a) = \left(\frac{y}{y_0}\right) \lg (1+\epsilon_r) \quad (A)$$

This Equation (A) is derived as follows:—

Taking as a starting point

$$x_n = (1+\epsilon_r)^n x_0$$

this may also be put down as follows:

$$10 \lg x_n = n \lg (1+\epsilon_r) + \lg x_0$$

$$or \quad n \lg (1+\epsilon_r) = \lg x_n - \lg x_0$$

$$or \quad 10 n \lg (1+\epsilon_r) = \lg \frac{x_n}{x_0}$$

consequently

$$15 n = \frac{\lg \frac{x_n}{x_0}}{\lg (1+\epsilon_r)}$$

In the same way it is possible to derive from

$$20 y_n = (1+\epsilon_a)^n y_0$$

$$n = \frac{\lg \frac{y_n}{y_0}}{\lg (1+\epsilon_a)}$$

It is possible therefore either to put down:

$$25 \frac{\lg \frac{x_n}{x_0}}{\lg (1+\epsilon_r)} = \frac{\lg \frac{y_n}{y_0}}{\lg (1+\epsilon_a)}$$

$$or \quad 30 [\lg (1+\epsilon_a)] \lg \frac{x_n}{x_0} = [\lg (1+\epsilon_r)] \lg \frac{y_n}{y_0}$$

$$or \quad 35 \left(\frac{x_n}{x_0}\right) \lg (1+\epsilon_a) = \left(\frac{y_n}{y_0}\right) \lg (1+\epsilon_r)$$

Since from the last equation the parameter n has been eliminated, this equation is valid not only for the points x_n, y_n , but also for any other points x, y ; it is therefore possible to put down the equation also in this form:

$$40 \left(\frac{x}{x_0}\right) \lg (1+\epsilon_a) = \left(\frac{y}{y_0}\right) \lg (1+\epsilon_r)$$

However, it appears also that any arbitrary point of the curve represented by this equation will again reach said curve due to the deformation 45 under the load p, q . Such a point x, y namely is transferred to

$$\bar{x} = (1+\epsilon_r)x$$

$$50 \bar{y} = (1+\epsilon_a)y$$

which coordinates indeed satisfy the Equation A for the curve, since substitution results in

$$55 \left\{ \frac{(1+\epsilon_r)x}{x_0} \right\} \lg (1+\epsilon_a) = \left\{ \frac{(1+\epsilon_a)y}{y_0} \right\} \lg (1+\epsilon_r)$$

$$(1+\epsilon_r) \lg (1+\epsilon_a) \cdot \left(\frac{x}{x_0}\right) \lg (1+\epsilon_a) = (1+\epsilon_a) \lg (1+\epsilon_r) \cdot \left(\frac{y}{y_0}\right) \lg (1+\epsilon_r) \quad 60$$

or, in connection with the Equation A

$$(1+\epsilon_r) \lg (1+\epsilon_a) = (1+\epsilon_a) \lg (1+\epsilon_r)$$

65 which is indeed an equality.

All the points of a meridian curve 2 therefore in the case of a deformation corresponding to the load p, q will lie again on the curve 2.

It should still be made acceptable that if the pressures p and q have each attained a predetermined fraction, only (αp) and (αq) of their final value the meridian curve of the deformed body is still represented by the Equation A, since it is an object of the invention to determine the me- 75

ridian curve of the matrix so that when relieving the pressure p the matrix permits the compressed mass to expand in such a manner that the pressure q decreases proportionally. To this end it 5 should be proved that with pressure αp and αq ($0 \leq \alpha \leq 1$), to which specific strains $\alpha \epsilon_a$ and $\alpha \epsilon_r$ correspond, the equation of the corresponding curve

$$10 \quad \left(\frac{x}{x_o}\right) \lg(1 + \alpha \epsilon_a) = \left(\frac{y}{y_o}\right) \lg(1 + \alpha \epsilon_r) \quad (B)$$

can indeed be identified with the Equation A.

In determining the meridian curve a number of points e. g. of the curve according to the Equation (A) are calculated and noted down, after which said points are approximately joined together by a smooth curve. If it is required, for example, that the said curve be a parabola, a little tolerance is to be used with regard to the 20 points which have been calculated and noted down.

Now:

$$\lg(1 + \alpha \epsilon_a) = \alpha \epsilon_a - \frac{(\alpha \epsilon_a)^2}{2} + \frac{(\alpha \epsilon_a)^3}{3} \dots$$

$$25 \quad \lg(1 + \alpha \epsilon_r) = \alpha \epsilon_r - \frac{(\alpha \epsilon_r)^2}{2} + \frac{(\alpha \epsilon_r)^3}{3} \dots$$

also if ϵ_a (the largest of the two ductile stresses) has the high value $1/10$, ϵ_a^2 will only have the 30 value $1/100$. Therefore there are no objections to write

$$\lg(1 + \alpha \epsilon_a) = \alpha \epsilon_a$$

$$\lg(1 + \alpha \epsilon_r) = \alpha \epsilon_r$$

35 so that the Equations A and B respectively may be written:

$$\left(\frac{x}{x_o}\right)^{\epsilon_a} = \left(\frac{y}{y_o}\right)^{\epsilon_r} \text{ and } \left(\frac{x}{x_o}\right)^{\alpha \epsilon_a} = \left(\frac{y}{y_o}\right)^{\alpha \epsilon_r}$$

40 from which it appears that the curves represent-

ed by said equations (apart from the slight values neglected) are identical, so that with a matrix according to the invention the purpose aimed at can indeed be attained, i. e. to press briquettes or tablets from powderlike and granular substances, which after the relief of the compression-pressure do not break up, by means of a press of exceedingly simple construction. It is obvious that in selecting the material and the machining of the mold care is to be taken that the coefficient of friction of the said material with regard to the material to be compressed is such that the said coefficient of friction will produce a shearing stress τ at the surface of the briquette which will satisfy the value theoretically required for the same, i. e. that the said shearing stress for every point of the surface of the briquette will equal, or practically equal

$$20 \quad \frac{p - q}{2} \sin 2\phi$$

in which ϕ represents the angle formed by the tangent drawn at the said point of the surface of the briquette and a horizontal line. It is obvious that in practical making of such a pressing mold 25 for constructing the meridian curve of the pressing mold a graphic approximation may be applied.

I claim:

A pressing mold for the manufacture of briquettes from fine grained materials, materials 30 in powder form, and the like, characterized in that the interior wall of the said mold is formed by the bounding surface of a solid of revolution, the generatrix of which surface satisfies the equation

$$35 \quad \left(\frac{x}{x_o}\right) \lg(1 + \epsilon_a) = \left(\frac{y}{y_o}\right) \lg(1 + \epsilon_r)$$

with respect to a coordinate system the y -axis of which coincides with the axis of rotation.

WILLEM BOLK. 40
